UNITED STATES PATENT OFFICE.

WILLIAM B. HUBBARD, OF SMITHBORO, ILLINOIS.

AUTOMATIC SASH HOLDER.

Application filed December 21, 1921. Serial No. 523,950.

To all whom it may concern:

Be it known that I, WILLIAM B. HUBBARD, a citizen of the United States, residing at Smithboro, in the county of Bond and State 5 of Illinois, have invented a new and useful Automatic Sash Holder, of which the following is a specification.

This invention relates to window constructions, the primary object of the invention 10 being to provide a window construction having novel means for holding the sashes thereof in various positions of adjustment.

Another object of the invention is to provide a device of this character including 15 spring means carried by the sashes and cooperating within the inner faces of the sash guides to set up a binding action therebetween.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawing:

30 Figure 1 is an elevational view of window sashes, portions thereof being broken away to illustrate the invention as applied.

Figure 2 is an enlarged sectional view of the sash holder; and

35 Figure 3 is a sectional view taken on line 3-3 of Figure 2.

Referring to the drawing in detail, the reference character 5 designates a window frame, which may be of any desired construction, the same being formed with suitable guideways 6 in which the sash members 40 7 move.

In the present invention, the usual weights and window cords have been supplemented 45 by sash holding devices forming the essence of the invention, each sash holding device embodying a tubular member 8 positioned

in a suitable opening formed within the side rail of the sash, one end of the tubular member being formed with beveled surfaces 9 to 50 receive the inclined walls 10 of the foot 11.

The foot 11 is formed with a shank 12 adapted to be fitted in one end of the coiled spring 13, the coils thereof being of diameters equal to the interior diameter of the tubular member in which the same is positioned. At the opposite end of the tubular member is positioned a head 14 which is also formed with a shank 15 fitted within the opposite end of the coiled spring 13. Thus it 60 will be seen that due to this construction, the tension of the coiled spring is sufficient to normally urge the foot 11 against the inner surface of the guideways setting up a binding action sufficient to support the 65 weight of a sash and secure the same in its positions of adjustment.

Having thus described the invention, what is claimed as new is:—

In combination with a window sash including side rails and the guideways in which the side rails move, said side rails having openings, tubular members positioned within the openings, each of said tubular members having a beveled surface formed 70 adjacent to the outer end thereof, a coiled spring positioned within the tubular member, a foot having a shank embraced by a portion of the coiled spring, said foot having inclined walls adapted to cooperate with the beveled surface of the tubular member 75 associated therewith, to permit the foot to be moved to a position flush with the outer edge of the tubular member, and said foot adapted to contact with the supporting bars 80 to support the window sash by frictional contact.

In testimony that I claim the foregoing as my own, I have hereto affixed my signature in the presence of two witnesses.

WILLIAM B. HUBBARD.
